(57) **CLAIM**

The ornamental design for an accelerometer, as shown and described.

DESCRIPTION

FIG. 1 is a lower perspective view of an accelerometer, showing our new design;

FIG. 2 is an upper perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The portions of the accelerometer shown in broken lines form no part of the claimed design.

The dashed-dotted line showings of FIGS. 1, 2, and 5-8 illustrate boundaries between the claimed design and environmental features.
